WRAPPER OR CONTAINER

Homer T. Huffield, Wethersfield, Conn.

Application February 5, 1938, Serial No. 188,883

2 Claims. (Cl. 229—51)

This invention relates to improvements in wrappers or containers which are especially adapted for packaging various commodities, and particularly, such as paper sheets.

As now commonly done, paper, or stationary, is packaged in two-piece boxes which consist of a lower container and a cover fitting over the top thereof. Such boxes, aside from being expensive are inconvenient and unsatisfactory in use for the reason that, when a number of such containers are stacked one upon the other, it is necessary to remove all of the boxes on top of a particular one in order that the cover thereof may be removed for access to its contents.

It is an object of this invention, therefore, to provide a blank which may be readily used as a wrapper to form, for, a quantity of paper sheets, or other commodity, a container which will not have the tendency to become unfolded and which may be stacked with other containers without being damaged.

A further object is to provide a container in which the ends thereof are normally locked in closed position but which can be altered to a predetermined form, by a simple operation, so that the said ends may be easily opened and closed when access is desired to the interior of said container.

Further objects and advantages of this invention will be readily understood from the following description and from the drawing in which:

Figure 1 is a plan view of a blank for a wrapper comprising my invention.

Figure 2 is a perspective view of the same shown in partly folded condition.

Figure 3 is a perspective view of the said blank in a completely folded condition and with parts broken away to show the construction of the carton formed thereby.

Figure 4 is a perspective view illustrating the end of said carton in open position after the same has been altered as provided for by my invention.

Figure 5 is a view similar to Figure 3 but showing the same altered in construction to permit opening of an end thereof.

As shown in the drawings, my improved carton or wrapper consists of a blank which is scored on lines 5, 6, 7, 8, 9, 10, 11 and 12 to provide a bottom 13, sides 14 and 15, ends 16 and 17, end flaps 18 and 19, side flaps 20, 21, 22 and 23, end flap extensions 24, 25, 26 and 27, and cover portions 28 and 29. The cover portion 28 is provided with slits 30—30 to receive ears 31—31.

The said blank is cut as illustrated at 9a—9a

and 10a—10a, by the heavy portions of score lines 9 and 10, to separate the flaps 20, 21, 22 and 23 from the side and cover portions. The said blank is also cut through as illustrated at 11a and 12a, by the heavy portions of the score lines 11 and 12, to separate the extensions 24, 25, 26 and 27 from the flaps 20, 21, 22 and 23.

It will be noted that I have provided on the said blank, tear lines 18a—18a and 19a—19a, on the end flaps 18 and 19, and tear lines 20a and 21a, 22a and 23a are also provided on the flaps 20, 21, 22 and 23 so that the said extensions 24, 25, 26 and 27 and flaps 20, 21, 22 and 23 may be torn off on their respective tear lines when desired for the purpose to be hereinafter pointed out.

When it is desired to wrap a quantity of paper sheets in my improved wrapper, the pile of sheets to be wrapped is first placed upon the bottom portion 13 of the wrapper blank. The said blank is then respectively folded on score lines 5, 6, 9 and 10, bringing the ends 16 and 17 against the pile of paper sheets. The flaps 20, 21, 22 and 23 are then folded, on the extensions of the score lines 5 and 6, against the sides of said pile. The end flaps 18 and 19 are then folded down upon the said flaps and the extensions 24, 25, 26 and 27 thereof are folded down on the extensions of score lines 5 and 6 against the sides of the flaps 20, 21, 22 and 23, as will be clearly seen from the illustration in Figure 2.

The cover portion 28 is then folded down upon the said pile, on the score line 7, and the cover portion 29 is folded on the score line 8 to overlie the portion 28. The ears 31—31 may be then inserted through the slits 30—30 to lock the wrapper in the condition illustrated in Figure 3 of the drawing.

In this condition, the flaps 20, 21, 22 and 23 are securely held in position by means of the cover portions overlying them so that the ends 16 and 17 are locked thereby and prevented from being pushed open by the weight of the contents of said carton. The end flaps 18 and 19 further serve to hold the paper sheets in position and, with their extensions 24, 25, 26 and 27, will reinforce the corners of the carton so that when a number of cartons are stacked one upon the other, each of the individual cartons will not collapse on account of the weight of the cartons and contents resting thereon.

An important object of my invention is attained by the provision of the tear lines above described which are provided on the said flaps

20, 21, 22 and 23 and on the end flaps 18 and 19, the purpose of which will now be described.

When it is desired to alter the condition of the carton so that a few sheets at a time may be taken out of the same without requiring removal thereof from the stack of cartons in which it may be positioned, the extensions at one end of said carton, or for instance, the extensions 26 and 27, may be torn off on the tear lines 18a-18a and on the portion of the score lines 5 and 6 thereon and the flaps 22 and 23 may be torn off on the tear lines 22a and 23a so that the carton may be opened from the end by permitting the ends 16 and 18 to be pulled out and thereby render access to the sheets of paper in said carton.

When it is desired to close the said end, the remaining portions of the flaps 22 and 23 are pushed back into the carton with the flap 18, thus returning the end 16 to its closing position.

It will be understood that the extensions 24, 25, 26 and 27 will serve to reinforce the corners of the carton during storage and shipment. The said portions may be torn off as desired by opening the carton, to the condition shown in Figure 2, and prior to stacking said carton in a position from which the paper is to be removed therefrom, at which time the contents of said cartons may also be inspected.

It will be understood from the above description that I have provided, by my invention, a wrapper which is particularly adapted to form a carton that is rugged in construction and highly efficient for the packaging of a commodity during the storage and transportation thereof and which may, by a simple operation, be altered to permit opening of said carton for removal of the contents thereof, as desired, without requiring that the same be taken out of a stack, in which it may be positioned.

I claim:

1. A container of the character described formed from a wrapper blank of sheet material including bottom, side, end and cover portions, side flaps on said end portions adapted to ex-

tend inwardly in said container and be positioned between the said bottom and cover portions to thereby retain the said end portions against displacement, end flaps on said end portions, and extensions on said end flaps for reinforcing the corners of said container; the said blank having score lines thereon defining the said extensions from the said end flaps, tear lines extending diagonally across the corners of said end flaps from said score lines to the free edge of said end flaps, and separate tear lines extending diagonally across the said side flaps; whereby the said extensions and corner portions of the end flaps may be torn off on a portion of the said score lines and on the tear lines across the corners of said end flaps, and a portion of said side flaps may be torn off on the score lines extending across the same, for altering the blank to a pre-determined form and thereby facilitating opening and closing of said container through the end thereof.

2. A container of the character described, comprising a wrapper of sheet material which is scored to provide the bottom, side, end and cover portions thereof, side flaps on said end portions adapted to extend inwardly in said container between the said bottom and cover portions to retain the said end portion against displacement, an end flap extending inwardly from an end portion, extensions from said end flap adapted to be folded downwardly and positioned between the said side flaps and side portions for reinforcing the corners of said container, and means whereby corner portion of said end flap, said extensions and portions of said side flaps may be torn off on pre-determined lines to facilitate opening and closing of said container from the end thereof; said means comprising score lines between said extensions and end flap, tear lines extending diagonally across the outer corners of said end flap from said score lines to the free edge of said end flap, and tear lines extending across the said side flaps.
